(57) **CLAIM**

The ornamental design for a gum massager with cap as shown and described.

DESCRIPTION

FIG. 1 is a perspective view of a gum massager with cap of the new design;

FIG. 2 is a side view of the gum massager with cap of FIG. 1;

FIG. 3 is a rear view of the gum massager with cap of FIG. 1;

FIG. 4 is a front view of the gum massager with cap of FIG. 1;

FIG. 5 is a further side view of the gum massager with cap of FIG. 1;

FIG. 6 is a top view of the gum massager with cap of FIG. 1;

FIG. 7 is a bottom view of the gum massager with cap of FIG. 1;

FIG. 8 is an exploded perspective view of the gum massager with cap of FIG. 1;

FIG. 9 is a perspective view of the cap of FIG. 1;

FIG. 10 is a further perspective view of the cap of FIG. 1;

FIG. 11 is a side view of the cap of FIG. 1;

FIG. 12 is a rear view of the cap of FIG. 1;

FIG. 13 is a front view of the cap of FIG. 1;

FIG. 14 is a further side view of the cap of FIG. 1;

FIG. 15 is a top view of the cap of FIG. 1; and,

FIG. 16 is a bottom view of the cap of FIG. 1.

Within figures showing dashed lines, the dashed line portions are included to show unclaimed subject matter and do not form part of the claimed design.

1 Claim, 6 Drawing Sheets
